CYLINDER TUNING OF CAVITY

Loy E. Barton, Collingswood, N. J., assignor to the United States of America as represented by the Secretary of the Navy

Application January 8, 1945, Serial No. 571,921

9 Claims. (Cl. 333—82)

The present invention relates to a tuning arrangement for an electrical resonant chamber adapted to be used at ultra high radio frequencies.

An object of the invention is to provide an electrical resonator adapted to accommodate a lighthouse tube and equipped with a simple and efficient tuning arrangement for the resonator.

Another object is to provide a continuously variable tuning cylinder for use in an electrical resonant chamber adapted for use in a high frequency radio system.

As is known in the art, a lighthouse tube is a disc-seal electronic vacuum tube for use at ultra high frequencies above 500 megacycles, in which the grid and anode connections protrude through the glass envelope in the form of parallel metallic rings spaced from one another along the length of the tube. The cathode is coupled to an outer metallic shell for the radio frequency current. One such lighthouse tube, mentioned by way of example only, is the General Electric type 446 triode. A description and illustration of this type of tube is given in the Science News Letter for August 19, 1944, page 115, and in the copending application of Goddard et al., Serial No. 487,722, filed May 20, 1943, now Patent No. 2,515,213.

A description of the invention follows in conjunction with a drawing, wherein:

Fig. 1 illustrates in cross-section the electrical resonant chamber and tuning arrangement of an embodiment of the invention;

Fig. 2 illustrates a side view of Fig. 1, partly broken away, taken along the line 2—2 of Fig. 2;

Fig. 3 illustrates the details of the tuning cylinder of Fig. 1; and

Fig. 4 illustrates the springy metallic washer used between the end plates of the cylinder of Fig. 3 and the walls of the resonant chamber.

The resonant chamber of Fig. 1 is especially designed to accommodate a "lighthouse" vacuum tube. The resonant chamber comprises a cylindrical metallic wall 1 electrically closed by metallic end plates 2 and 2'. The end plate 2 is provided with a circular opening or aperture 3 for enabling the grid and anode rings of the lighthouse tube (not shown) to enter its interior. Concentrically positioned around circular aperture 3 and connected to end plate 2 is a metallic cylinder 4 which is provided at its open end with annularly arranged metallic contact fingers 5 for engaging the metallic cathode shell of the lighthouse tube. Also mounted on end wall 2 in the interior of the resonant chamber but insulated therefrom, from a direct current standpoint, by means of a mica insulation ring 6, is an annularly arranged ring of metallic contact fingers 7 for engaging the grid ring of the lighthouse tube.

Contact fingers 7 and contact fingers 5 are resilient in character to enable the lighthouse tube to be easily inserted into the resonator and to assure good electrical contact with the vacuum tube elements.

A cylindrical metallic tube 8 is fastened to the con-

2

tact fingers 7 by means of a metallic flange 9, in turn soldered to the tube 8. It will thus be seen that metallic tube 8 forms an extension, so to speak, of the grid contact arrangement 7. A block of insulation 10 serves to clamp the assemblage of contact fingers 7 and metallic tube 8 to the end plate 2 of the resonant chamber.

Another metallic tube 11 is located in the interior of the resonant chamber and serves to engage the anode or plate electrode stub of the lighthouse tube. Metallic tube 11 is secured at one end to a metallic plate 22, in turn mounted on end plate 2'. An annular insulation ring 12 of mica serves to insulate the tube 11 from end plate 2', from a direct current standpoint. A block of insulation 10' serves to clamp the assemblage of metallic tube 11 and plate 12 to the end plate 2'.

For tuning the electrical resonant chamber there is provided in the interior of the chamber a rotatable metallic cylinder 13 which is cut to leave approximately one-half of the wall area. This is shown in more detail in Fig. 3. Tuning cylinder 13 is provided with metallic end walls 13'. One end wall 13' is provided at its center with a round stub which passes through an aperture in the end plate 2 of the resonant chamber, while the other end wall 13' is provided at its center with a round shaft 14 which passes through an aperture in end plate 2' of the chamber. The cylinder is rotated by means of shaft 14. Tuning cylinder 13 is provided with a wedge-shaped slot S in order to provide a linear relation between the change in frequency and angular rotation of the cylinder.

Positioned between each end wall 13' of the tuning cylinder and the adjacent end plate 2 or 2' of the chamber is a metallic resilient ring 15 having a multiplicity of springy segments in order to assure good electrical contact between the cylinder ends and the end plates of the resonant chamber. Resilient ring 15 is shown in more detail in Fig. 4.

Polarizing potential for the anode of the lighthouse tube is supplied from a metallic stub 16 (note Fig. 2) which is connected to the metallic tube 11 through a choke coil 17. Metallic stub 16 is insulated from the resonant chamber by means of an insulation bushing, not shown.

A condenser is formed by the insulation ring 12 which insulates the metallic tube 11 from the end plate 2' of the resonant chamber. In effect, this condenser is an isolating condenser for direct current, and serves to by-pass energy of the operating frequency from the anode electrode of the lighthouse tube to the end plate 2' of the resonant chamber.

A condenser is also formed by the insulation ring 6 and this condenser is effectively coupled across the grid and cathode of the lighthouse tube. The value of this condenser determines the amount of radio frequency voltage supplied to the grid relative to that generated on the anode.

The resonant chamber, together with its associated lighthouse tube (not shown), may be used in an ultra high frequency system of the type described in detail in my copending application Serial No. 571,920, filed January 8, 1945, for Lighthouse Tube Oscillator, now Patent No. 2,627,577, in which case a grid return choke in the form of a wire about one inch long should be connected between the metallic tube 8 and the cylinder wall 1 of the resonator.

In the operation of the tuning mechanism of the invention, the tuning cylinder 13 may be so rotated by shaft 14 as to cause the solid section B illustrated in Fig. 1 to be nearest to the tube 8, in which case the approximate effective length of the resonant chamber is given by dimension L1. In this position, the current path along the inside of the resonator is the shortest, the inductance of the resonator is at its lowest value,

and the frequency at its highest value. When the tuning cylinder 13 is turned about 180° from the above position, the effective length of the resonant chamber will be given by the summation of the dimensions L1 and L2, in which position the current path along the inside of the resonator is the longest, the inductance of the resonator will be at its greatest value, and the frequency at its lowest. At intermediate positions, the current paths will be different from the two above extremes, and the frequency of operation will be between the highest and lowest values.

The larger the cylinder 13 is with respect to the cavity of the chamber, the greater will be the tuning range.

One advantage of the present invention is that the cylinder and shaft arrangement eliminates the need for complicated screw and sliding arrangements used in more conventional tuning systems.

Other advantages lie in the fact that the system is dustproof when the vacuum tube is inserted, and there is no back-lash present when the cavity is tuned.

In one experimental embodiment of the invention, the resonant chamber and tuning arrangement of Fig. 1 was used in an oscillator circuit employing a lighthouse tube to generate oscillations of a frequency above 500 megacycles, and a wide tuning range of more than 100 megacycles was obtained.

It should be noted that the resonant chamber, by virtue of the metallic extension tube 8, approximates a concentric line resonator in form, and for this reason it should be understood that the invention is not limited to the particular configuration of resonator illustrated.

What is claimed is:

1. A tuning element for an electrical resonator comprising a rotatable metallic cylinder having half the cylindrical surface area cut away and having a wedge-shaped cut in the non-cut away area thereof.

2. An electrical resonator for use at ultra high frequencies and adapted to accommodate a lighthouse tube, comprising a cylindrical metallic wall provided with metallic end plates, one of said end plates having a circular aperture therein; a metallic tube mounted on the outside of said one end plate in concentric relation to said aperture, said metallic tube having annularly arranged contact fingers for engaging the cathode shell of the lighthouse tube, and another metallic tube fastened to said one end plate in the interior of said resonator and also arranged in concentric relation to said aperture, said last metallic tube being provided with annular contact fingers for engaging the grid ring of said lighthouse tube, and a third metallic tube mounted coaxially relative to said aperture but located in the interior of said chamber and secured to the other end plate of said chamber for engaging the anode electrode of said lighthouse tube, and a tuning element inside said chamber, said tuning element comprising a rotatable metallic cylinder having an appreciable portion of its surface area cut away, the axis of rotation of said cylinder being parallel to the axes of said metallic tubes, the ends of said rotatable cylinder being electrically connected to the end plates of said chamber, said rotatable cylinder having a length substantially equal to the distance between said end plates.

3. A tuning element for an electrical resonator comprising a rotatable metallic cylinder having half the cylindrical surface area thereof cut away and a wedge-shaped slot cut in the non-cut away surface area thereof symmetrically positioned about a plane perpendicular to the axis of rotation thereof.

4. An electrical resonator comprising a substantially closed cavity structure having a dimension which determines the resonant frequency thereof, and means for

varying said dimension comprising a hollow semi-cylindrical member having a length dimension substantially equal to the cavity dimension perpendicular to said dimension rotatably mounted within the cavity about an axis perpendicular to said dimension and asymmetrically positioned with respect to the cavity.

5. An electric resonator comprising a substantially closed cavity structure having a dimension which determines the resonant frequency thereof, and means for varying said dimension comprising a hollow semi-cylindrical member having a length dimension substantially equal to the cavity dimension perpendicular to said dimension rotatably mounted within the cavity about an axis perpendicular to said dimension and asymmetrically positioned with respect to the cavity, and said member having a wedge-shaped slot cut in the surface thereof symmetrically positioned with respect to a plane perpendicular to said axis.

6. An electrical resonator comprising a substantially closed cavity structure having a dimension which determines the resonant frequency thereof, and means for varying said dimension comprising a hollow cylindrical member having a length dimension substantially equal to the cavity dimension perpendicular to said dimension rotatably mounted within the cavity about an axis perpendicular to said dimension and asymmetrically positioned with respect to the cavity, said cylindrical member having an appreciable portion of the surface area thereof cut away.

7. An electrical resonator comprising a substantially closed cavity structure having a dimension which determines the resonant frequency thereof, and means for varying said dimension to tune the cavity comprising a hollow cylindrical member having a length dimension substantially equal to the cavity dimension perpendicular to said dimension rotatably mounted within the cavity about an axis perpendicular to said dimension and asymmetrically positioned with respect to the cavity, said cylindrical member having an appreciable portion of the surface area thereof cut away and a wedge-shaped slot cut in the non-cut away surface area thereof symmetrically positioned with respect to a plane perpendicular to said axis.

8. In an electrical resonator, a substantially closed cavity structure, a hollow conductor positioned in said cavity perpendicular to one dimension thereof, and means for tuning the cavity, the last-named means comprising a hollow semi-cylindrical member having a length dimension substantially equal to said one dimension rotatably mounted within the cavity in spaced relation from the conductor about an axis parallel thereto.

9. In an electrical resonator, a substantially closed cavity structure, a hollow conductor positioned in said cavity perpendicular to one dimension thereof, and means for tuning the cavity comprising a hollow semi-cylindrical member having a length dimension substantially equal to said one dimension rotatably mounted within the cavity in spaced relation from the conductor about an axis parallel thereto, and said member having a wedge-shaped slot cut in the surface thereof symmetrically positioned with respect to a plane perpendicular to said axis.
